(57) **CLAIM**

The ornamental design for a treadmill belt, as shown and described in FIGS. 1 through 5.

DESCRIPTION

FIG. 1 is a perspective view of a treadmill with a first embodiment of a treadmill belt according to the invention, the treadmill belt comprising slats with a grass-like upper surface. FIG. 2 is a perspective view of the treadmill belt of FIG. 1. FIG. 3 is a top plane view of the treadmill belt of FIG. 1. FIG. 4 is a side elevational view of the treadmill belt of FIG. 1.

FIG. 5 is an elevational view of the front or rear end of the treadmill belt of FIG. 1; and,

FIG. 6 is an enlarged view of the area encircled in FIG. 2. The broken line showing of a treadmill is included for the purpose of illustrating environment and forms no part of the claimed design.
